UNITED STATES PATENT OFFICE.

WINTHROP K. HOWE, OF ROCHESTER, NEW YORK, ASSIGNOR, BY MESNE ASSIGNMENTS, TO THE G. B. S. PRODUCTS, INC., OF COLONIE, NEW YORK, A CORPORATION OF NEW YORK.

SAFETY WRINGER CONTROL FOR WASHING MACHINES.

Application filed November 12, 1919. Serial No. 337,526.

To all whom it may concern:

Be it known that I, WINTHROP K. HOWE, a citizen of the United States, and resident of the city of Rochester, in the county of Monroe and State of New York, have invented a new and useful Improvement for Safety Wringer Controls for Washing Machines, of which the following is a specification.

10. This invention relates to combined power operated washing machines and wringers, and more particularly to an improved safety control for the wringer.

In washing machines of the type now commonly used, the wringer is running all of the time while clothes are being wrung out. Many serious accidents have occurred with such wringers. Frequently, the fingers or hand of the operator are caught and drawn 20 into the wringer rolls; and sometimes the operator's hair has been caught while she has been stooping down to get clothes for the next wringing. Also, it is found that power operated wringers are very destructive to clothes, particularly in breaking or tearing off buttons. This is largely due to the fact that the operator, after getting a garment started in the wringer, has little chance to arrange it to protect the buttons 25 or fix the buttons so that they will be fed into the wringer rolls properly. Power operated wringers are commonly provided with a handle for starting, stopping and reversing the wringer rolls, and also, generally 30 a safety tension release device; but these devices are ordinarily very awkward to reach, require the use of a hand, and in practice are rarely used because of the resultant inconvenience and delay. Moreover, in case 35 the operator is unexpectedly caught in the wringer, it is practically impossible to stop the wringer rolls or release their tension quick enough to avoid serious injury; and besides, as a general rule, when such an accident occurs, the operator is panic-stricken 40 and may not think of reaching for those handles which are used so rarely.

In my improved wringer control I propose to have the wringer rolls normally stationary and provide some means, preferably a treadle, which the operator can easily and conveniently use to start the rolls and keep them going while a garment is being wrung

out, the rolls being instantly stopped when the operator lets up the treadle. Thus, in accordance with my invention, the wringer rolls do not move until the operator is ready, with the result that, except in the case of extreme carelessness, the operator's hands and hair, or the like, are out of the way, and the garment to be wrung has been put in position to be caught by the rolls. Furthermore, the wringer rolls automatically stop as soon as the treadle is released, this stopping movement, being frequently and regularly used, becomes an automatic or subconscious act, so to speak, and something which the average person would instinctively do if an accident should occur. Finally, the operator has complete control over the wringer rolls and is able to avoid tearing of clothes and the ripping off of buttons.

Other detail features and advantages of my improvements will appear as the description of the invention progresses, and the novel features of the invention will be particularly pointed out in the appended claims.

In describing the invention in detail, reference will be made to the accompanying drawings, in which like reference characters designate corresponding parts in the several views, and in which:

Figure 1 shows in elevation one side of a washing machine, with my improvement applied thereto, certain parts being broken away or shown partially in section for clearness;

Fig. 2 is a detail view showing the clutch for starting and stopping the wringer rolls;

Fig. 3 shows in enlarged section a modified construction of the clutch for stopping and starting the wringer rolls;

Fig. 4 is a transverse section of the washing machine taken substantially on the line 4-4 in Fig. 1, looking in the direction indicated by the arrows, and showing among other things how the plunger operating lever is supported by the frame of the washing machine; and

Fig. 5 is a similar transverse section taken substantially on the line 5-5 in Fig. 1, looking in the direction indicated by the arrows, which shows in plan the construction of the treadle, together with the means for supporting it.

Figs. 6 and 7 show an auxiliary treadle

which is preferably employed when the washing machine is used in connection with two stationary washtubs; and

5 Figs. 8 and 9 illustrate a modified construction employing a portable foot control device.

Referring to Fig. 1, the washing machine to which my invention is applied, and which by itself forms no part of my present invention, comprises in general a main supporting frame, consisting of four legs 1 and a number of cross bars 2 to give rigidity to the frame; a metallic tank or tub A, preferably constructed of galvanized metal 10 or copper, supported within said frame; a drum or cylinder (not shown) for holding the clothes to be cleansed and rotatably mounted within said tub; a load shaft 3 adapted to be shifted into and out of operative connection with said drum by a handle 4; and operating mechanism suitably enclosed, preferably in a unitary casing C fastened at three points to the frame. An electric motor M of any suitable type is operatively connected by an insulated friction clutch connection to a high speed worm 5 which meshes with a worm gear 6 secured to the lower end of a vertical main drive shaft 7. This drive shaft 7 is hollow and carries, 15 near its middle, a low speed worm 8 which meshes with a worm gear 9 journaled on a stud mounted in the back of the mechanism casing C. A pitman or connecting rod 10 carries a fixed pin 11 at one end which is journaled in an eccentric hole in the low speed worm gear 8, and is pivotally connected at its opposite end to one of the arms 20 of a gear sector 12. This gear sector 12 is journaled on a pin 12¹ fixed in the back wall of the mechanism case C, and meshes with a pinion 13 secured to the load shaft 3; and when power is applied to the motor, the gear sector 12 is rocked up and down 25 and rotates the pinion 13 and the load shaft 3 through substantially a complete revolution first in one direction and then in the opposite direction.

The wringer W used in connection with the washing machine may be any suitable usual power-operated type. I have shown a wringer having the quick-acting tension release; and although this is not essential when my improved wringer control is used, as will be hereinafter explained, it is nevertheless useful for releasing the rolls when the clothes become bunched while wringing. The wringer W is mounted on a laterally extending arm 14 of a wringer support S which is mounted on a vertical tubular extension 15 integral with the mechanism casing C, so that the wringer may be swung horizontally to a plurality of different wringing positions. A plunger 16 locks the wringer support S against movement in each of these several positions. The usual

reversing gearing, by means of which the wringer rolls can be rotated in either direction, comprises two opposing bevel-gears 17-18 loosely journaled on a wringer drive shaft 19 coupled to one of the wringer rolls. This shaft 19 is journaled at its ends in bearings formed in a housing 20 forming an integral part of the wringer support S. These bevel-gears 17-18 are constantly in mesh with a bevel-pinion 21 secured by a pin to the upper end of a vertically disposed stub shaft 22 which extends downwardly through the wringer support S and within a supporting tube 23 which is threaded into said wringer support. The wringer drive shaft 19 carries a clutch member 24 which is splined to a sleeve secured by pins to said shaft, and which can be shifted by a handle 25 into operative relation with either of the bevel-gears 17 or 18 to drive the wringer shaft in either direction.

Referring now to the parts constituting the present invention, (see Figs. 1 and 2) the stub shaft 22 hereinbefore mentioned, is provided at its lower end with clutch teeth 26 and a downwardly extending guiding spindle 27 of smaller diameter than the shaft, which fits loosely into an axial recess in a clutch member 28, this spindle serving to keep the two clutch parts in alignment. The clutch member 28 is also provided at its lower end with a similar spindle 29 which fits loosely in the upper end of the main hollow drive shaft 7. A transverse pin 30 in the lower end of said spindle 29 fits loosely in elongated vertical slots 31 in the upper end of the main drive shaft 7.

Extending lengthwise of the main drive shaft is a plunger rod 32 having an enlarged head at its upper end confined between the spindle 29 and a sleeve 33 pinned thereto, so as to constitute a swivel connection between said rod and the clutch member 28. The rod 32 projects at its lower end through a stuffing box 34 in the bottom cap of the worm gear housing; and a jaw 35 is fastened to the lower end of said rod. A compression spring 36 between the jaw 35 and the cap of the worm gear housing gives a downward bias to the rod 32 and tends to keep the clutch member 28 disengaged from the stub shaft 22. The jaw 35 is pivotally connected to one end of a rocking lever 37 which is fulcrumed near its middle in a block 38 bolted to a cross plate 39 attached to the main frame of the machine, (see Fig. 4). The other end of the rocking lever 37 is pivotally connected to a short rod 40 which in turn is connected to a treadle T.

The treadle T, as best shown in Fig. 5, comprises an open frame 41, shaped to conform to the outline of the machine, and four cross members 42, which are fastened to each side of the frame 41 and are threaded

into a center piece 43, the short rod 40, above mentioned, being adjustably connected to this center piece 43. The frame 41 is preferably made up of two pieces of tubing bent into the desired shape, and having their ends overlapped and fastened together by bolts 44 where two of the cross members 42 are connected. The corners of the frame 41 are guided in downwardly opening slots 45 in corner blocks 46, secured to the legs 1 by screws or other means, (see Figs. 1 and 5). Thus, the frame of the treadle is suspended from its middle and is held up by the spring 36. The treadle T is preferably located near the floor so that it may be depressed by merely rocking the foot.

The operation in my improved wringer control will be readily apparent, and need only be briefly explained. While the motor is running, the drive shaft 7 and the clutch member 28 are constantly rotating; but the spring 36 keeps this clutch members 28 out of engagement with the stub shaft 22, so that the wringer rolls are stationary. To start the wringer, the operator presses down on one side of the treadle T. This pulls down on the short rod 40, the treadle acting as a lever with its fulcrum at the corner blocks 46 opposite to that where the pressure is applied. The lever 37 is rocked, and the plunger rod 32 moved up against the opposition of the spring 36, to bring the clutch teeth on said member and the shaft 22 into engagement, thereby rotating the stub shaft 22, and through the gears 21-17, or 21-18, as the case may be, turning the wringer rolls in one direction or the other, depending upon the setting of the handle 25. To stop the wringer, the operator merely releases the treadle T, whereupon the spring 36, aided by the weight of the clutch members 28 and the rod 32, returns the parts to the normal position. Pressure may be applied to any part of the frame 41 of the treadle at any side or corner of the machine, the fulcrum point being correspondingly shifted to the opposite corner block or blocks 46. The handle 25 is used merely to select the direction of rotation of the wringer rolls, although, if desired, it also may be used to stop the rolls.

Instead of the toothed clutch shown in Figs. 1 and 2, a friction clutch, such as shown in Fig. 3, may be employed. This gives the operator more complete control over the wringer, allowing her to start and stop it, and run it fast or slow. In this modified construction, the stub shaft 22 terminates at its lower end in a squared and tapered portion fitting into a counterpart recess in a boss 47 of a cylindrical clutch casing 48. This detachable connection permits the wringer support S, together with the stub shaft 22, to be removed from the machine, whenever desired. The clutch

shown is of the multiple disc type and comprises a plurality of annual metal plates 49 and 50 arranged alternately, with rings or washers 51 of fibre or similar friction material between them. The plates 49 are provided with integral projecting tongues fitting in grooves 52 in the inside of the clutch casing 48, so that these plates must turn with said casing but may slide toward each other. In a similar way, the plates 50 have tongues fitting in slots 53 cut in the upper end of the main drive shaft 7, so that these plates 50 turn with said drive shaft. A follower 54 rests on the upper end of the rod 32 and has arms 55 extending out through the slots 53 underneath the lowest plate 49. A reinforcing cap 56 is preferably put on the upper end of the main shaft to prevent splitting or spreading of its slotted end. The operation of this friction clutch will be evident. When the rod 32 is moved upward by a depression of the treadle, as previously explained, the follower 54 compresses the plates 49 and 50 and the friction washers 51, thereby transmitting rotation from the main drive shaft 7 to the stub shaft 22. By varying the pressure upon the treadle T, this clutch may be slipped to any extent desired, so as to drive the wringer rolls fast or slow. On account of the flexibility of the operator's control over the wringer rolls, afforded by a friction clutch of the type described, the maximum running speed of the rollers may be increased, thereby shortening the wringing operation.

Referring to Figs. 6 and 7, when the washing machine is used with the two stationary washtubs, as 60 and 61, commonly found in modern houses, the machine is usually placed in front of one of the tubs, as 60, in the position shown in Fig. 6; and when it is desired to wring clothes from rinsing or blueing water in the tub 61 into a basket 62, the wringer W is swung to the position shown in Fig. 6. While feeding the wringer in this position the operator ordinarily finds it most convenient to stand over by the end of the tub 61; and standing in this position, it is practically impossible for her to reach the main treadle D under the machine. In order to avoid the necessity of moving the machine, when it is desired to perform the wringing operation illustrated in Fig. 6, I preferably employ an auxiliary treadle D. This auxiliary treadle D is fulcrumed near its middle point on a portable block 63, and is provided at one end with a socket 64 adapted to fit over the jaw 35 on the lower end of the clutch operating rod 32. The other end of the auxiliary treadle D is shaped to form a foot plate 65, and in order to keep the socket 64 normally in engagement with the jaw 35, this outer end of the treadle D is preferably made heavier. The treadle D is extended underneath the tub

61 as shown in Fig. 6, and when the foot piece 65 is depressed, the clutch operating rod 32 is raised to start the wringer rolls in the same way as previously described. This 6 auxiliary treadle D may be detached and stored away when not in use, or may be left in position as desired.

In the modified construction shown in Figs. 8 and 9, I employ a portable foot control device E having a flexible operating connection with the clutch for starting and stopping the wringer rolls, so that this foot control device may be moved about by the operator in convenient position. Fig. 8 also 10 shows a modified form of clutch construction, which is operated by a downward pull upon the rod 32, rather than a upward push as in the case of Figs. 1 and 3. Referring to Fig. 8, the lower end portion of 15 the wringer operating shaft 22 is made square or triangular in cross section and has a detachable and sliding fit with a similar shaped socket 66 in an upper clutch member 67. The lower clutch member 68 is provided with lugs 69 which fit in slots 70 in 20 the upper end of the main drive shaft 7, so that said lower clutch member turns with said drive shaft. These upper and lower clutch members 67 and 68 are provided with 25 clutch teeth 71 in the usual way. A compression spring 72, having its ends in recesses in the clutch members 67 and 68, keeps 30 these members normally separated. The clutch operating rod 32 extends lengthwise 35 through the clutch members 67 and 68, and its enlarged head bears against the bottom of the socket 66. When the rod 32 is pulled down, clutch members 67 and 68 are drawn 40 together, and when released, the spring 72 forces them apart.

The foot control device E comprises a box-like portable stand 73 with an enlarged base 74. An angle lever 75 is pivotally mounted on a pin 76 supported in the sides of the 45 stand 73, said lever being provided with a foot plate 77. A flexible conduit or tube 78 formed of coiled wire or the like, is fastened at one end to a packing nut 79 in the lower cap of the casing for the worm gear 6, and at its other end to a boss 80 integral with the stand 73. The ends of the conduit 78 may be 50 screwed into the nut 79 and the boss 80, as shown, or may be clamped or otherwise fastened therein. A flexible wire 81 inside of the conduit 78 is clamped at one end into the slotted lower end of the operating rod 32 by a nut 82, and is fastened at its other end to the short arm of the angle lever 75. A 55 detachable cover 83 is provided on the stand 73 to facilitate the connection of the wire 81 to the lever 75. The ends of the conduit 78 being anchored to the machine and the stand 73, respectively, when the foot plate 77 is depressed, the wire 81 is pulled, thereby 60 drawing down on the rod 32 and engaging

the clutch members 67-68; and when the foot plate 77 is released, the spring 72 disengages said clutch members. This action occurs regardless of the position of the stand 73 with respect to the machine. This portable foot control device may be used with or without the treadle T under the machine, such as shown in Fig. 1; and also, a friction clutch, such as shown in Fig. 3, may be used instead of the clutch members 67-68, 75 shown in Fig. 8.

Regarding the distinctive advantages of my improved wringer control, it will be noted that the wringer rolls, being normally stationary, cannot accidentally injure the 80 operator. When the operator is ready and desires to start the wringer, she may do so by simply pressing down on the treadle T. This is a simple and convenient movement which may be done while on any side of the 85 machine, and which leaves the operator's hands free to manipulate the clothes as they are being drawn into the wringer. If the operator sees the clothes tangling up or bunching, or buttons going between the rolls 90 sideways, she may instantly stop the wringer by merely releasing the pressure on the treadle. Furthermore, if it should happen that the operator gets her hands or hair caught in the wringer she instinctively 95 releases the treadle and stops the wringer, since such action will have become automatic by regular and constant use. My improvement, therefore, has two important 100 safety characteristics, first, the possibility of the operator getting caught in the wringer is eliminated largely, except where the operator is thoughtless or careless, and second, even if such accident should occur, the 105 dangerous results are minimized because the wringer is quickly stopped automatically as the result of an instinctive movement on the part of the operator.

These safety characteristics are obtained by the simple and effective arrangement and construction of parts, which is so arranged 110 that the safety wringer control may be applied to the machine or left off, as desired, without material modification in the construction of the regular operating mechanism for the washing machine. When the safety wringer control is left off, it is only necessary to change the construction of the stub shaft 22 so that it will make a detachable driving connection directly with the 115 main drive shaft 7.

My improved wringer control is also constructed so that it will operate on the safe side in case of such breakage or injury as may occur in practical use. If the treadle, or any part of its connection to the clutch up to the rod 32, should break, the clutch will still be disconnected and the device operated on the side of safety. If the rod 32 120 should break, the clutch element will re- 125

lease. This is evident in the case of the friction clutch shown in Fig. 3, since the driving connection ceases as soon as pressure is relaxed; in the construction shown in Fig. 2, the clutch teeth are preferably shaped so as to have a slight tendency to push apart. In this connection, while I have shown the spring 36 for disengaging the clutch applied to the lower end of the rod 32, it is evident that a similar spring, by a simple and obvious rearrangement of parts, could be applied directly to the two clutch elements.

Although I have particularly described the construction of one physical embodiment of my invention, and explained the operation and principle thereof; nevertheless, I desire to have it understood that the form selected is merely illustrative, and does not exhaust the possible physical embodiments of the idea of means underlying my invention.

What I claim as new and desire to secure by Letters Patent of the United States, is:—

1. In a combined power operated washing machine and wringer, the combination with a wringer and normally inactive driving means therefor, of a foot controlled member extending on all sides of the machine and supported on a single pivot for controlling said driving means, said foot controlled member as it is operated and released automatically rendering said driving means active and inactive respectively.

2. In a combined power operated washing machine and wringer, the combination with a swinging wringer and normally inactive driving means therefor, controlling means for said driving means including an operating member, and treadle means adjacent the sides of the machine suspended wholly from said operating member for operating said controlling means.

WINTHROP K. HOWE.
